TRACTOR MOUNTED CRANE

Robert G. Le Tourneau, Peoria, Ill., assignor to
R. G. Le Tourneau, Inc., a corporation of California

Application August 15, 1938, Serial No. 224,977

7 Claims. (Cl. 212—67)

This invention relates to cranes, and particularly to one of a light-duty type, adapted to be mounted on a tractor and especially designed for use in picking up bundles of sugar cane in the field, though the crane is by no means limited to such use.

The crane includes a turnable mast and a boom connected together as a rigid unit, and the main object of the invention is to so mount and control the operation of this unit that the mast at the base is kept entirely clear of projections, operating cables and the like which might interfere with the lifting and manipulation of relatively long bundles, while enabling the overhang of the boom to be relatively short.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of my improved crane showing the same as mounted on a tractor.

Figure 2 is a top plan view of the structure detached.

Figure 3 is an enlarged fragmentary vertical section of the mast and boom.

Figure 4 is a fragmentary sectional plane showing the entry of one of the mast swing cables into a beam of the supporting framework.

Figure 5 is a similar view showing the entry of one of the lifting cables into said beam.

Referring now more particularly to the characters of reference on the drawings, the crane comprises a pair of horizontal hollow side beams 1 connected as a rigid unit at front and back by crossbeams 2. This unit is maintained at a desired height above the tractor 3 on which the structure is mounted by uprights 4 depending from the front corners, and other uprights 5 depending from the rear corners. The uprights are secured at their lower end on the frame of the tractor in any suitable manner; the length of the beams 1 and 2 being substantially the same as the length and width respectively of the tractor. Another crossbeam 6 connects the beams 5 adjacent the bottom, the beam 6 being disposed somewhat rearwardly of the rear crossbeam 2.

A number of power control units or power winches, one of which is indicated at 7, are mounted at the front end of the tractor in driv-

ing relation with the power plant thereof. The operation of said units is controlled by the driver of the tractor from his seat thereon by levers 8 disposed in depending relation to the frame beams 1 and connected to the different power units by linkage and lever connections 9. The mast 10, which is located directly behind the tractor centrally thereof, is of tubular form and is mounted at its ends on top and bottom antifriction bearings 11 and 12. The bottom member of the lower bearing is directly supported from the lower crossbeam 6 while the top member of the upper bearing is supported from a plate 13 projecting rearwardly from the upper rear crossbeam 2.

The boom 14, in the form of a single hollow beam, projects upwardly and rearwardly from the mast near its base and radially thereof, and terminates in a horizontal portion 15 disposed at a level some distance above the top of the mast. The boom is braced by a member 16 which extends forwardly from the boom at the top and radially of the mast to a connection with a large circular turntable 17 rigid with the mast adjacent its upper end. The turntable is provided with a pair of vertically spaced circumferential grooves 18 to receive operating cables 19. These cables extend about the grooves from opposite directions, being secured at one end on the turntable, and then leave the grooves at the front at a tangent and pass through the corresponding beams 1, as shown in Fig. 4. At the front end of the beams, each of said cables passes about a direction changing pulley 20 and thence to the corresponding power unit. The cables 19 are prevented from leaving their grooves by means of an endless guard band 21 disposed about the turntable and mounted rigid with the rear crossbeam 2; the brace member 16 making connection with the turntable from below as shown in Fig. 3. The boom may thus be swung through an arc of substantially 180°, and it will be seen that the turntable as well as the operating cables are well clear of the lower end of the mast. Besides, the cables are enclosed where they extend along the tractor, and do not interfere in any way with the movements of the operator, nor are they a source of danger in the event of breakage.

The lifting hooks 22, of which there are two, are supported from separate lift cables 23. These pass upwardly over sheaves 24 hung to the sides of the boom from a supporting sleeve 25 adjustably slidably along the horizontal portion 15 of the boom. Each cable then passes over a pulley 26 mounted on the side of the boom adjacent the forward end of portion 15, then down

to the mast and over another pulley 27 fixed on the mast between the boom and brace member. The pulley 27 projects into the hollow interior of the mast to adjacent the axis thereof. The 5 cable extends upwardly from said pulley inside the mast, through an opening in the top bearing 11, and over a direction changing pulley 28 fixed on plate 13. The pulley 28 extends in a lateral direction so that the cable after passing 10 over said pulley also extends toward one side of the structure. The cable then extends about another direction changing pulley 29 fixed on the rear crossbeam just back of the corresponding side beam 1 in such relation thereto that the 15 cable enters the beam inwardly of the adjacent cable 19 as shown by a comparison of Figs. 4 and 5. At the front end of beam 1, cable 23 passes down to its power control unit over a final direction changing pulley 30 disposed alongside the 20 adjacent pulley 20.

It will thus be seen that the two lift cables may be independently manipulated, and as is the case with the boom swing cables, the lift cables, for the length of the tractor, are completely enclosed and are out of the way. The leading of the lift cables into and then out of the mast at the top enables the boom to be swung without any appreciable movement of the lift cables.

From the foregoing description it will be readily seen that I have produced such a device as substantially fulfills the objects of the invention as set forth herein.

While this specification sets forth in detail the present and preferred construction of the 35 device, still in practice such deviations from such detail may be resorted to as do not form a departure from the spirit of the invention, as defined by the appended claims.

Having thus described my invention, what I 40 claim as new and useful and desire to secure by Letters Patent is:

1. A crane comprising a turnable mast, a boom rigid therewith, said boom having a horizontal portion at its rear end, a pair of separate laterally spaced lift cables, separate direction changing pulleys about which the cables pass, and a sleeve slidably mounted on said horizontal portion of the boom and from which both said pulleys are directly supported in laterally spaced 50 relation.

2. A crane comprising a mast, a boom projecting therefrom, means adapted to be mounted on a tractor at one end turnably supporting the mast, a turntable mounted on the mast, said 55 turntable being formed with a pair of vertically spaced grooves about its outer periphery, a pair of pull cables anchored at one end on the turntable and extending about the grooves from opposite sides of the turntable, said cables projecting 60 from the turntable tangent thereto, and a fixed band about and adjacent the grooved portion of the turntable, said band having openings through which the tangential portions of the cables pass.

3. A crane comprising a supporting structure 65 which includes hollow side beams, means to

mount said beams lengthwise on and above a tractor, a mast at one end of the structure, means between the structure and the mast turnably supporting the mast at its ends, a boom supported by the mast, a turntable rigid with the mast on the same level as said beams and substantially the same diameter as the spacing between the beams, pull cables projecting through the beams to and wrapped about the turntable from opposite sides thereof, a lift cable supported 10 from the boom and means including direction changing pulleys training said cable from the boom through one of said beams so as not to interfere with the swinging of the boom.

4. A crane comprising a supporting structure 15 which includes side beams one of which is hollow, means to mount said beams lengthwise on a tractor, a mast turnably supported on said structure at one end thereof, a boom supported by the mast, control means to rotate the mast, a lift 20 cable supported from the boom and means including direction changing pulleys training said cable from the boom through the hollow beam so as not to interfere with the swinging of the boom.

5. A crane comprising a hollow turnable mast, a boom supported from the mast, mounting means for both ends of the mast, said means at the upper end of the mast including a fixed plate overhanging the top of the mast and having an 30 opening concentric with and communicating with the interior of the mast, a lift cable supported by the boom, a direction changing pulley on the mast below its upper end and training said cable into the mast and a fixed direction changing 35 pulley on said mounting plate above the mast to and about which the cable extends from said mast pulley, said plate pulley being substantially tangent on one side to the axis of the mast.

6. A crane comprising a hollow mast, means 40 to turnably mount the mast on the rear end of a tractor so that the lower end of the mast is relatively close to the ground, a boom supported by the mast, a lift cable depending from the outer end of the boom, a pulley secured on the mast intermediate its ends and projecting into the hollow interior thereof, and a fixed direction changing pulley mounted above and overhanging the mast, the cable extending from the boom and into the mast about the first named pulley, 45 and then up in the mast to and about said direction changing pulley for engagement with a control unit.

7. A crane and operating mechanism therefor comprising a boom, means to mount the boom 55 on a tractor at the rear end thereof and including a frame member adapted to be disposed at a predetermined level above the tractor, a lift cable for the boom, a power control unit including a drum for said cable adapted to be mounted on the front end of the tractor and means to control the unit including a lever supported and depending from the frame member in front of the operator's seat on the tractor.

ROBERT G. LE TOURNEAU.
